UNITED STATES PATENT OFFICE.

CHARLES E. WILLIAMS, OF CHICAGO, ILLINOIS.

TELEPHONE EARPIECE OR RECEIVER.

Application filed March 5, 1923. Serial No. 622,882.

To all whom it may concern:

Be it known that I, CHARLES E. WILLIAMS, a citizen of the United States, residing at Chicago, in the county of Cook and State 5 of Illinois, have invented a new and useful Improvement in Telephone Earpieces or Receivers, of which the following is a specification.

My present invention relates to improvements in telephone ear-pieces or receivers, and has special reference to the variety of telephone ear-pieces or receivers which are employed in microphone apparatus for the use of persons whose hearing is impaired. 10 Persons with impaired hearing can usually hear different characters of sound with different degrees of readiness, and different transmitters have been provided, each of which is capable of amplifying and transmitting with greater emphasis different character of sound. Also apparatus is made in which a number of different transmitters have been combined in a single circuit with a single ear-piece, or pair of ear- 15 pieces, so that by selecting suitable transmitters the sound which the person hears will be rendered more normal, readily understood and pleasing. A number of such transmitters have been produced which are 20 extremely sensitive and desirable, but it is found that not more than six of such transmitters can advantageously be inserted in a circuit carrying approximately three volts of current and that if a current with a 25 greater voltage is employed the carbon granules in the transmitter pass a fluctuating current which causes a sound in the ear-piece or receiver, generally described as frothing, which materially interferes with 30 the transmission of the desired sounds.

The object of my present invention is the provision of an ear-piece or receiver of the microphone type with which an increased number of transmitters may be connected. 45 I prefer to carry out my invention by means of the instrumentalities illustrated in the accompanying drawings, in which

Fig. 1 is a central section of a conventional form of microphone ear-piece or receiver in which my invention is embodied.

Fig. 2 is a view of the structure shown in Fig. 1 looking toward the cap or closure but with the cap or closure and diaphragm removed, and

Fig. 3 is a diagrammatic view of the cir-

cuits involved in the operation of my invention.

Similar reference characters refer to similar parts throughout the several views.

The usual microphone ear-piece or receiver comprises a casing 10, preferably formed in whole or in part of an insulating material, such as hard rubber. The casing is usually of cylindrical form and open at one end. Around the open end, the casing 60 is exteriorly threaded to receive the interiorly threaded flange of a centrally apertured cap 11. The flange of the cap is thickened somewhat at its base to provide an interior annular shoulder 12, which comes 65 opposite the edge of casing 10, and between the edge of the casing and shoulder is secured a diaphragm 13.

Secured to the interior face of the bottom of the casing by any suitable means, such as 70 the machine screws 14, is a plate 15 to diametrically opposite portions of which are secured, as by machine screws 16, brackets 17 of magnetically permeable material. These brackets may be described as of 75 J-shape, the hooked ends 17^a being secured to plate 16, and the stem portions 17^b extending toward and alining with each other. The ends of the stem portions opposite to the hooks have lateral projections 17^c which 80 extend in parallel relation toward and closely adjacent to diaphragm 13.

In the usual form of microphone ear-piece or receiver each stem portion 17^b is provided with a single coil 18^a and 18^b of magnet wire 90 electrically connected in series and included in the circuit coming from the transmitter.

But, as heretofore alluded to, the present transmitters cannot operate to advantage in a circuit having an electro motive force in 95 excess of three volts, and no more than six such transmitters can be advantageously operated in such a circuit. I have, therefore,

provided each stem portion 17^b of brackets 17 with an additional coil 19^a and 19^b which 100 are themselves electrically connected in series, but which have no electrical connection with the other two coils.

When the circuit of which coils 19^a and 19^b form a portion are energized with a current of substantially three volts, or such as can be produced with two commercial dry cells, any number of transmitters less than seven may be interposed in the circuit, and the action of these additional transmitters upon the diaphragm 110

will be combined with the action of the transmitters in the circuit of which coils 18^a and 18^b form a portion. In Fig. 3, I have indicated the circuits involved in the practice of my invention. In Fig. 3 18^a and 18^b indicate one pair of coils, and 19^a and 19^b the other pair of coils. The coils 18^a and 18^b are connected in series in the circuit comprising conductor C' and battery D', and 10 transmitters E', while coils 19^a and 19^b are connected in series in circuit comprising conductors C², battery D² and transmitters E². In this manner the possibility of adapting an instrument to the needs of a particular patient are increased without disadvantageously effecting the action of the respective elements of which the instrument is composed.

What I claim is:

20 1. In an instrument for assisting the partially deaf including a plurality of independent electric circuits, each of which includes a plurality of microphones in series, a telephone ear-piece or receiver including 25 an electro-magnet having independent coils

included in the respective afore-mentioned circuits.

2. In an instrument for assisting the partially deaf, including two independent electric circuits each of which includes a plurality of microphones in series, a telephone ear-piece or receiver including an electro-magnet having two independent pairs of coils, each pair of coils being included in one of the aforementioned circuits. 35

3. A telephone ear-piece or receiver comprising a casing, an apertured closure therefor, a diaphragm secured to said casing by said closure and opposite the aperture thereof, elements of magnetically permeable material mounted in said casing and extended adjacent to said diaphragm, independent coils of conductor encircling said elements, and conductors extending between said coils to form a plurality of independent circuits, 45 and a plurality of microphones included in series in each of said independent circuits. 40

Signed at Chicago, county of Cook and State of Illinois, this 27th day of Feb., 1923.

CHARLES E. WILLIAMS.
